Letters Patent No. 77,237, dated April 28, 1868.

IMPROVED APPARATUS FOR RAISING SUNKEN VESSELS.

The Schedule referred to in these Letters Patent and making part of the same.

TO ALL WHOM IT MAY CONCERN:

Be it known that I, GEORGE M. ALLERTON, of the city and State of New York, have invented and made a certain new and useful Improvement in Apparatus for Raising or Sustaining Vessels; and I do hereby declare the following to be a full, clear, and exact description of the said invention, reference being had to the annexed drawing, making part of this specification, wherein—

Figure 1 is a cross-section of a vessel with my improved apparatus applied thereto.

Figure 2 is a side view of a portion of a vessel and said apparatus.

Similar marks of reference denote the same parts.

Heretofore it has been usual to attach floats to the sides of vessels by means of ropes and chains passed beneath said vessel or around the ends. In many situations it is difficult and almost impossible to connect the floats by these means, in consequence of the vessel being embedded in mud or sand, or resting upon a stony bottom. Besides this, the shape of the floats has usually been such that they were not adapted to any other character of fastenings; being generally of a conical or spheroidal form.

These floats have usually been made with a netting of ropes, concentrating at one or two points, and under strain it is often found that these ropes break, and the inflated bag, being unsupported, bursts from the pressure. Such bags sometimes also burst in consequence of the bag suddenly coming up to or near the surface of the water, where the pressure of the water being less, allows the contained air to expand with greater force than the bag can sustain.

The nature of my said invention consists in a float formed of an air-tight bag, within a casing of woven or similar material, formed so as to be spiked upon the side of the vessel by a sufficient number of spikes passing through the said casing. I provide a sufficient number of these floats, placed along the sides of the vessel, and as far down as possible, and said floats may be a little distance apart, or they may be lapped or placed in several rows or banks, according to the buoyant power required. I supply each of these bags with air from a main pipe, and provide an escape-pipe at the bottom, so that the air may freely pass away if the pressure becomes too great.

In the drawing, *a* represents a portion of a vessel or other article to be raised. *b b* are the air-bags, made of an oblong form, with the supply-tube *c* at the upper end, and each provided with a cock or valve, *c'*, and connected to the main air-tube *d*, that passes up to the air-pump. The cock or valve *d'* is used to allow air to escape, if required.

Each air-bag has a tube, *e*, passing away from its lower end, to allow of the escape of air when the bag is filled, and the pressure becomes too great. This tube may be of any desired length, so that the end remains open to the water at the lowest and most dense portion thereof, or said pipe may be provided with a safety-valve or other appliance, to retain the air to a given pressure. This valve acts as a weight, to keep the lower end of the tube down, and a cord may be attached to draw up the tube and valve, when required.

f is a casing, into which each air-bag is introduced. Separate casings may be made for each bag, or said casings may be adapted to receive two or more of said bags.

Each casing is adapted to form a complete enclosure for the air-bag, in order that it may be fully sustained, and the material of which said air-bag is formed relieved of as much strain as possible. By this construction the air-bag may be of thin India rubber, sufficient to be air and water-tight; the strength being derived from the casing.

The casing is to be made of a woven or netted fabric, or netting of a character adapted to the strength required, and provided with gromets or eyelets all around the edges, so that spikes or bolts can be introduced as frequently as necessary for attaching said casing firmly to the article to be raised.

The number of spikes, and the extent of surface into which they hold, prevent injury by undue strain at one point, as is often the case where chains are employed, and the eyelets allow the floats to be laced together when most convenient.

The floats can be attached well down under the vessel's counter, so as to actually act beneath, and hence strain the fastenings but little.

Floats attached in this manner are not liable to break loose from the vessel, and are not in the way in towing the vessel after it has been raised.

By connecting all the air-bags on one side of the vessel to the main pipe *d*, the multitude of flexible tubes usually employed to lead from the pump to each bag is avoided, and all the floats on one side of the vessel can be first charged to right her, and then the floats on the other side be charged, or the two ranges of floats may be charged simultaneously.

What I claim, and desire to secure by Letters Patent, is—

1. A series of casings, provided with eyes around their edges, to be secured to the vessel by spikes, in combination with separate air-bags introduced within said casings, and capable of inflation, as and for the purposes specified.
2. An escape-air tube, extending below the air-bag, substantially as and for the purposes set forth.
3. A series of air-bags, connected to the supply-pipe *d* by the tubes *c*, in combination with cocks *c'* *d'*, as and for the purposes set forth.

In witness whereof, I have hereunto set my signature, this twelfth day of February, 1868.

GEO. M. ALLERTON.
